PLIER STRUCTURE

John H. Melchers, Minneapolis, Minn.

Application December 20, 1943, Serial No. 514,926

1 Claim. (Cl. 81—51.5)

This invention relates to a tool such as a plier or pair of pincers, and particularly to such a tool having jaws with opposed faces, which jaws are moved rectilinearly toward and from each other. In gripping and handling many articles and objects by means of a plier it is more convenient to have the jaws moved toward each other in a straight line rather than in a curved line.

It is an object of this invention to provide a simple and efficient structure of plier having jaws with opposed faces, which jaws are movable rectilinearly toward and from each other.

It is a further object of the invention to provide a plier having a jaw member which is movable in guideways formed in another member of said pliers so that said jaw member is guided rectilinearly.

It is another object of the invention to provide a plier comprising members pivoted together and having portions constituting the handles of said plier, one of said members having one or more guideways formed therein and extending transversely thereof and having a jaw formed thereon together with a jaw member having portions movable in said guideways and having a jaw thereon aligned with said first mentioned jaw, said jaw member being connected to the other of said members whereby when said handle portions are moved toward and from each other said jaws will move toward and from each other parallel to said guideways.

It is more specifically an object of the invention to provide a plier construction comprising a member having a channel shaped portion and forming one handle of said plier, said member having projecting slightly spaced plate portions, a second substantially straight member having a jaw at one end and an end portion forming the other handle of said plier, said second member also having a flat portion adjacent said jaw disposed between said plate portions, said flat portion having one or more rectilinear guideways formed therein and extending transversely thereof, a pivot connecting said members, a jaw member having a jaw aligned with said first mentioned jaw and having one or more laterally projecting portions fitting in and slidable in said guideways together with a connection between said first mentioned member and said jaw member whereby when said first mentioned member and second member are moved toward and from each other said jaws will be moved toward and from each other parallel to said guideways.

These and other objects and advantages of the invention will be fully set forth in the following

description made in connection with the accompanying drawing in which like reference characters refer to similar parts throughout the several views and in which—

- 5 Fig. 1 is a view in side elevation of the plier embodying the present invention;
- 10 Fig. 2 is a view in vertical section taken substantially on line 2—2 of Fig. 4 as indicated by the arrow;
- 15 Fig. 3 is a view similar to Fig. 1 showing the plier in open position, a portion being broken away;
- 20 Fig. 4 is a partial view in front elevation as seen from the left of Fig. 3;
- 25 Fig. 5 is a horizontal section taken on line 5—5 of Fig. 3 as indicated by the arrows;
- 30 Fig. 6 is a view in side elevation showing a modification, some parts being broken away; and
- 35 Fig. 7 is a horizontal section taken on line 7—7 of Fig. 6, as indicated by the arrow.
- 40 Referring to the drawing, a plier construction is shown comprising a member 10. While this member could be variously formed, in the embodiment of the invention illustrated it is in the form of a channel having side portions 10a and a connecting web portion 10b. Said web portion 10b is cut away or omitted adjacent one end of member 10 so that the side portions 10a project as flat parallel plate portions 10c at one end of said member. Member 10 as shown in Fig. 1, is of curved
- 45 55 form in side elevation and tapers toward its free end. Another member 11 is provided in the shape of a bar, the same being connected to member 10 by means of a pivot 12 which may be of any convenient form and is illustrated as in the form of a headed rivet. Member 11 from pivot 12 curves somewhat away from member 10 and then is reversely curved toward member 10, the same tapering somewhat toward its free end. Member 11 is of a thickness to fit between the sides 10a of member 10 and the curved portions of members 10 and 11 at one side of pivot 12 constitute the handle portions of said plier. Member 11 has a flat portion 11a beyond and adjacent pivot 12 and has its terminal end formed as a jaw 11b having a face 11c. Portion 11a has formed therein a plurality of guideways 11d. As shown in Fig. 4, there are two spaced guideways at one side of member 11 and one at the other and they are of trapezoidal or dove-tailed shape in cross section. A jaw member 13 is provided having a jaw portion 13a thereon which is aligned with jaw portion 11a and has a face 13b. Jaw member 13 has spaced portions 13c projecting laterally therefrom and shaped to fit in and be slidable in the guideways 11d. Portions 13c are thus also of trapezoidal or dove-

tailed shape in cross section. The tops of portions 13c are flush with the outside surfaces of portion 11a. A connection is provided between member 10 and member 13 and while this might take various forms, in the embodiment of the invention illustrated it comprises a pin 14 disposed in member 13 and projecting from each side thereof into slots 10d formed in the plate portions 10c.

With the described construction it will be seen that when the curved portions of members 10 and 11 are moved toward or from each other about pivot 12, that jaw member 13 will be caused to move toward or from member 11 due to the sides of slot 10d acting upon pin 14. The portions 13c slide in the guideways 11d and the jaws 11b and 13a thus move toward and from each other parallel to guideways 11d. Since guideways 11d extend transversely of member 11 and are rectilinear, the jaws 11b and 13a and their faces 11c and 13b move toward and from each other rectilinearly. An article or object having flat sides or parallel flat sides can thus be conveniently gripped between the outer ends of jaws 11b and 13a.

In Fig. 6 a modified form of the invention is shown comprising a member 20 of channel shape, the same having projecting parallel plate portions 20a at one end. The channel shaped end portion of member 20 constitutes one handle of the plier. Another member 21 is provided in the form of a straight bar, the same having a jaw 21a formed on one end thereof, which jaw extends generally at an angle to the longitudinal center line of member 21 and has a face 21b also extending at an angle to said center line. Member 21 has a flat portion 21c adjacent jaw 21a which is of a thickness to fit snugly between the plate portions 20a. The end portion of member 21 beyond portion 21c constitutes the other handle of the plier. Members 20 and 21 are connected adjacent portion 21c by a pivot member 22 preferably in the form of a headed rivet. A resilient plate spring 23 has one end secured in a slot 21d formed in one edge of member 21, said spring extending between the sides of member 20 and having its other end engaging the web portion 20b of member 20. Portion 21c has spaced guideways 21e formed therein at each side thereof, which guideways are rectilinear and extend transversely of member 21 substantially at right angles to its longitudinal center line. A jaw member 24 is provided, the same having a jaw 24a formed thereon with a face 24b, which face extends substantially parallel to face 21b. Member 24 has laterally projecting portions 24c spaced and shaped to fit in the guideways 21e. Portions 24c and guideways 21e are preferably of trapezoidal or dove-tailed shape in cross section. The outer sides of portions 24c are flush with the sides of portion 21c and thus fit between plates 20a. A connection is provided between member 20 and member 24 and while this could take various forms, in the embodiment of the invention illustrated it comprises a pin 25 secured to member 24 and projecting from each side thereof, the projecting portions being disposed in slots 20c formed in the portions 20a.

In operation it will be seen that when the handles of the plier are moved toward each other, that jaw member 24 will be moved toward member 21 due to the sides of slots 20c acting on

pin 25. The movement of jaw 24a toward jaw 21a will be parallel to the guideways 21e and thus rectilinear. When the handle portions of members 20 and 21 are moved toward each other spring 23 is placed under tension and when pressure is released from said handles said spring will move said handles away from each other. Member 21 is of course, of a thickness to move into the channel of member 20.

From the above description it will be seen that I have provided a very simple and very efficient construction of plier in which the jaws move rectilinearly toward and from each other. The movement of the jaws is very accurate and any tendency for a twisting movement which might occur when pressure is placed on certain objects between the jaws is prevented by the dove-tailed shape of the portions moving in the guideways. These are portions 13c in Figs. 1 to 5, and portions 24c in Fig. 6. The handle members of the plier can be made of small thickness and yet the same are strong and rugged. The plier is easily operated and works with precision. Due to the spaced plate-like portions on one member and the flat plate-like portion of the other member disposed between said portions and having the guideways therein a tool of small thickness can be produced. This is quite a desideratum. A neat and efficient tool is thus provided. The device has been amply demonstrated in actual practice and found to be very successful and efficient.

It will of course, be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claim.

What is claimed is:—

A plier construction having in combination, a member having one end portion forming one handle of said plier and having spaced plate-like portions at its other end, a second member having an end portion forming the other handle of said plier and having a jaw at its other end and a flat bar-like portion integral with said jaw and intermediate said jaw and handle, said bar-like portion being disposed between said plate-like portions, a pivot member connecting said members so that they have only relative movement oscillating about the axis of said pivot, said bar-like portion having transverse rectilinear shallow guideways formed on both sides thereof, a jaw member having a jaw alined with and opposing said jaw and having spaced transversely extending projections fitting in and slidable in said guideways, said projections having their outer surfaces flush with the outer sides of said bar-like portion, said projections being disposed and movable between said plate-like portions, a pin in said jaw member located adjacent said projections and alined cam slots in said plate-like portions in which the ends of said pin are disposed, whereby when said handle portions are moved toward and from each other about said means, said jaws are moved toward and from each other in a direction parallel to said guideways.

JOHN H. MELCHERS.
